UNITED STATES PATENT OFFICE.

RAY ACRE, OF CHICAGO, ILLINOIS.

DESIGN FOR A RADIOCABINET.

Application filed July 1, 1926. Serial No. 18,221. Term of patent 7 years.

To all whom it may concern:

Be it known that I, RAY ACRE, a citizen of the United States, residing at 28 North Clinton Street, in the county of Cook and State of Illinois, have invented a new, original, and ornamental Design for Radiocabinet, of which the following is a specification, reference being had to the accompanying drawing, forming part thereof.

Fig. 1 is a perspective view showing my new design; and

Fig. 2 is a top plan view of Fig. 1.

I claim:

The ornamental design for a radiocabinet, as shown.

RAY ACRE.
